UNITED STATES PATENT OFFICE.

FRANKLIN HAWES, OF BOSTON, MASSACHUSETTS, ASSIGNOR TO THE LAMBERT MANUFACTURING COMPANY, OF NEW YORK, N. Y.

CLAW FOR HAMMERS.

SPECIFICATION forming part of Letters Patent No. 661,717, dated November 13, 1900.

Application filed August 17, 1900. Serial No. 27,180. (No model.)

To all whom it may concern:

Be it known that I, FRANKLIN HAWES, of Boston, in the county of Suffolk and State of Massachusetts, have invented certain new and useful Improvements in Claws for Hammers, of which the following is a specification.

This invention has for its object to provide an improved adjustable claw for hammers; and it consists in the novel features of construction and arrangement of parts hereinafter described and claimed.

Reference is to be had to the accompanying sheet of drawings, forming a part of this application, and to the figures of reference marked thereon, the same reference characters designating the same parts or features wherever they occur.

Of the drawings, Figure 1 represents in side elevation and partly in section an adjustable claw constructed in accordance with my invention and mounted in place on a hammer, the figure also showing in dotted lines one of the adjusted positions of the claw. Fig. 2 is a detail sectional view of the same, a portion 25 of the claw being broken away to show the relative position of parts, the pins in Fig. 2 being shown released in order to swing the claw while the detents in Fig. 1 are closed. Fig. 3 represents a cross-sectional view on the 30 line 3 3 of Fig. 1. Fig. 4 represents a detail view of the claw. Fig. 5 represents in front elevation the spindle and its connected parts.

Referring to the drawings, 1 represents the handle of a hammer 7, that has the usual apertured hub 2 for the reception of a reduced portion 3 of the handle. The hammer has the customary driving-head 4.

20 represents my improved claw. This, as shown, is cored out, as at 21, the open end of 40 the core being countersunk, as at 22. The hub of the hammer opposite the end 4 is cored out, as at 30. Midway the ends of this core the walls of the recess are formed with screw-threads 31. The claw 20 is formed with a reduced hub 23, arranged to fit loosely in the core 30.

40 represents a spindle formed on its outer end with screw-threads 41. The inner end of the spindle is enlarged and provided with 50 screw-threads 42. The outer end of the spindle is cored, as at 43, to receive a spring 44.

45 represents a pin arranged in an aperture in the central part of the spindle 40, the spring bearing at one end upon the lower wall of the recess 43 and at its upper end against the head 55 of the spindle. The inner end of the screw-thread enlargement 42 is centrally cored, as at 36.

46 represents a collar secured to the inner end of the pin 45 and formed with a central 60 hub 47, arranged in the recess 36. The collar 46 is further provided with two pegs 48 48, arranged to slide in complementary pairs of holes 49 49, formed in the adjacent walls of the core 21 and the spindle 40, said holes being continued through the screw-threaded enlargement 42. The pin 45 is normally held outward, or in the position shown in Fig. 1, by the spring 44. Upon depression of the pin 45 against the spring the collar 46 will be 70 moved inward, removing the pegs 48 from the position shown in Fig. 1, where the parts are locked, to the position shown in Fig. 2, where the pegs are withdrawn from the inner ends of their recesses 49, so that the inner ends of 75 the pegs are in the screw-threaded enlargement 42, thereby leaving the claw 43 free to be rotated about the spindle 40. The parts being constructed as described and shown, the spindle, with its pin, (see Fig. 5,) is inserted in the core 21, the screw-threads 42 engaging the screw-threads 31, thus firmly locking 80 the spindle to the hub of the hammer.

70 represents an internally-threaded nut 85 whose screw-threads are arranged to engage the screw-threads 41 on the outer end of the spindle, the nut being of a size to firmly engage the walls of the countersunk portion 22, the lower end of the nut engaging the lower wall of the countersunk hole. The screw-threads 31 and 42 lock the spindle to the hub 90 of the hammer, while the nut 70 prevents the claw from being removed from the spindle.

80 represents a pin for locking the threads 42 in place. (See Fig. 2.) Supposing the claw 95 to stand in the position shown in full lines in Fig. 1 and it is desired to have it occupy the position shown by dotted lines in Figs. 1 and 3 or at a right angle thereto either at the top or the bottom, the pin 45 is depressed, 100 as heretofore described, moving the collar inward and releasing the claw from the pegs 48.

The claw can then be rotated about the spindle 40 to the desired position, and the pegs can then be moved to engage the holes 49 and retain the claw in the desired adjusted position.

While I have shown four holes, and those so arranged that the claw may be adjusted to four different positions, I do not wish to be understood as limiting my invention to that degree of adjustment, since the same means could be employed for adjustments of varying degrees by varying the position of the holes.

By my invention the claw of the hammer can be adjusted to any position in order to readily engage the head of a nail or tack or other object. This is of great advantage, since in many situations it is impossible or difficult to engage the claw of the ordinary hammer with the head of a nail or other object. By my invention the claw can be readily adjusted to a position where the engagement can be readily effected. Further, the claw and hub and their associated parts are provided with such substantial bearing engagements that the parts are united together with strength sufficient to stand the different strains to which the claw is subjected.

While I have shown and described my invention in connection with a hammer, I do not wish to be understood as limiting the application of my invention to that particular implement, as it is designed and intended for use in connection not only with hammers, but also hatchets, axes, and, in general, with the various tools and implements wherein claws are or may be employed.

The collar 46 and the pegs 48 thereon are hereinafter referred to as a "locking device" and the pin 45 as an "operating member" which enables the locking device to be manipulated. The said locking device positively secures the claw in different positions to which it may be adjusted, and its location

within the hub makes it inaccessible to dust 45 and dirt, the projecting operating member 45 enabling it to be readily manipulated.

Having thus explained the nature of my invention and described a way of constructing and using the same, though without attempting to set forth all of the forms in which it may be made or all the modes of its use, what I claim, and desire to secure by Letters Patent, is—

1. An improved implement, comprising a hub, a claw, and an adjustable spindle-and-socket connection between the claw and hub, whereby the claw may be adjusted to varying positions, and a locking device whereby the claw may be positively secured in different positions to which it may be adjusted.

2. An improved implement, comprising a hub, a socket formed therein, a spindle secured in said socket, a claw rotatably mounted on said spindle, a locking device within the socket whereby the claw may be locked in different positions upon the spindle, and an operating member projecting from the socket whereby the locking device may be manipulated.

3. An improved implement, comprising a hub, a socket formed therein, a spindle secured in said socket, a claw loosely mounted on said spindle but maintained in operative relation thereto, a pin arranged in said spindle and carrying on its inner end a collar, means upon said collar for engagement with said claw, the parts being so arranged that by the movement of said pin the claw will be released for adjustment, and thereafter locked in adjusted position.

In testimony whereof I have affixed my signature in presence of two witnesses.

FRANKLIN HAWES.
